UNITED STATES PATENT OFFICE.

GEORGE FRANCIS MYERS, OF NEW YORK, N. Y.

FLYING MACHINE.

Application filed January 19, 1911, Serial No. 603,524. Renewed March 6, 1920. Serial No. 363,667.

To all whom it may concern:

Be it known that I, GEORGE FRANCIS MYERS, a citizen of the United States, resident at New York city, in the county of New

5 York and State of New York, have invented new and useful Improvements in Flying Machines, of which the following is a specification.

10 My invention relates to flying machines and comprises certain novel constructions and combinations of parts, hereinafter described and specifically pointed out in the claims.

15 In general, the present application is in the nature of an improvement on my companion application filed May 31, 1904, Serial No. 210,486.

20 In detail, the present application is in the nature of an improvement on another companion application filed May 31, 1910, Serial No. 564,223.

25 In the said first mentioned companion application I show an aeroplane having two separate and substantially unobstructed and independent advancing edges or peripheries one following the other; the shape or conformation of both the said outer and the said inner peripheries being similar—that is both are circular in shape; and they are 30 concentric, some of the same being curved in cross section. But I did not "limit myself to the peripheral conformation" of the said peripheries; and therefore in the present application I now show a similar unitary aeroplane with dissimilar peripheries, the outer one being still circular in conformation as in the said first mentioned companion application but the inner periphery thereof being rectangular in shape.

40 In the said last mentioned companion application I also show a similar aeroplane as in the said first mentioned companion application, that is to say the shape or conformation of the two peripheries is still circular, but the centers of the said two peripheries are eccentric one to the other; in this and in other details the said last mentioned companion application and the present application are similar and show a more 45 highly developed machine than the said first mentioned companion application.

The said first mentioned companion application has since become Patent No. 995,550.

50 In the drawings, Fig. 1 is a plan view of a machine embodying my invention. Fig. 2

is a side elevation showing the machine having left its truck but still attached thereto by its cord. Fig. 3 is a front elevation of the machine.

55 Referring to the drawings, 1 is an aeroplane and 2 the fuselage thereof, the opening 3 being directly behind said fuselage. In this opening is the propeller 4 and directly to the rear of the opening are the ailerons 5 and 6 hinged on the axis 7.

60 The framework of the aeroplane 1 is composed of longitudinal bars 8 and transverse bars 9 and 10. The ailerons 5 and 6 are also constructed in like manner. The ends of the bars 8, 9, and 10 are all connected by the ring 11 except those longitudinal bars whose ends project to the rear of the transverse bar 10, these are not connected but are left free and flexible.

65 The front curved periphery of the said aeroplane, of course, forms an advancing edge to the impinging air. But when the aeroplane is moving through the air in a normal condition, that is in a substantially straight line and in stable equilibrium the said ailerons form a second surface for the impinging air to act upon, as they are not moving as ailerons or rudders, giving the air therefore two advancing edges following one another to strike against: one on the advancing edge on the front portion of the aeroplane, and also an additional advancing edge on the front portion of the now motionless ailerons, thereby forming 70 practically two surfaces connected by side connections comprising surfaces, all forming substantially a unitary surface or aeroplane.

75 The front edges of the said ailerons lie 75 preferably in a straight line, the opening in front thereof being angular in shape, preferably rectangular. It is in this said opening that the propeller is preferably placed. The rear of the said ailerons are 80 also preferably made with flexible edges.

85 Looking at the aeroplane from the side, it will be seen that the front surface, that is the surface in front of the opening 3, is normally at a positive angle of incidence to the horizontal, as shown more fully in Fig. 3; the front advancing edge being higher than the edge directly in front of the said propeller. This surface is curved from front to rear with its concaved side facing 90 downwardly.

95 The second or following surface consti-

tuting the ailerons is also curved, but the chord thereof is placed at a negative angle of incidence to the horizon, and therefore the two said surfaces constituting the aero-
5 plane are at different angles relatively one to the other along the longitudinal center line of the machine. These ailerons are rigidly curved upwardly similarly to the ailerons shown in my companion applica-
10 tion Serial No. 575,911, the ailerons in the present application being in the nature of an improvement on the said ailerons.

The curve of the aeroplane as a whole is a double reverse curve like the letter S; 15 first curving upwardly and then downwardly and finally upwardly again at the rear edge thereof.

Looking at the machine from the front it will be seen that the aeroplane is bell 20 shaped transversely.

The ailerons 5 and 6 are free to move on the bar 10 independently one of the other by means of the quadrants 12, operating cables 13 running over pulleys 14 and 15 25 and being attached to the levers 16 and 17 in the fuselage 2. The handles to the levers 16 and 17 are conveniently placed in front of the seat 18 of the operator.

The box 19 placed on the upper part of 30 the aeroplane preferably conforms to the upper curve of the aeroplane and may contain a safety device.

The truck 20 is preferably composed of two angle bars 21 suitably braced, and depending therefrom four forks 22 shackled to the pontoon 23. However when used more particularly for land service wheels 24 shown in dotted lines may be used. A cord 25 is wound up on a spring controlled roller 26, the free end of said cord terminating in the ring 47 and being placed over the hook 27 having a spring end 28.

At the front of the fuselage 2 is placed the radiator 50, and directly in the rear 45 thereof the motor 39. On the sides of the fuselage 2 are pivoted slats or valves or ports 51.

The operation of the machine is essentially as follows: When ready to make a 50 flight the aeroplane is lifted onto the truck 20, the bottom of the skids 29 resting on the angle bars 21 of the said truck. The ring 47 of the cord 25 is placed over the hook 27 and the propeller 4 started. As the 55 truck with the machine moves forward the ailerons 5 and 6 are slightly lowered by the operator bringing down the forward portion of the machine, the skids 29 rocking over the angle bars 21 into the front bend the said angle bars. Head resistance is thus 60 reduced to a minimum. When the requisite speed has been acquired the ailerons are raised which lifts the forward part of the machine and causes it to ascend as shown 65 in Fig. 2. The truck however is pulled

along by the cord 25 until it slips off the hook 27 either due to the angularity of the end of said hook, or by the weight of the truck pulling on the said cord and overcom-
70 ing the action of the spring at the end of said hook, or otherwise.

The cord 25 is then instantly wrapped around the spring controlled roller 26 and the end of the propeller 4 easily clears the truck 20. When the operator wishes to turn to the right for instance he manipulates the lever 16 which will operate the rudder or aileron 5, and the machine will turn to the right. If he wishes to turn to the left the left hand lever 17 is used operating the rudder 6. If he wishes to ascend or descend both the levers 16 and 17 are handled as if they were one lever; that is both the rudders are operated together or simultane-
80 ously, and in the same direction. If he 85 wishes to stabilize laterally, he uses both of the said levers simultaneously but works them in opposite directions or reversely, and the machine will be righted.

In alighting the propeller 4 may be 90 turned if necessary from its vertical position shown in Fig. 2 to the horizontal position as in Fig. 3.

It must be remembered that I may make 95 various changes in the form, proportion, size and detail of the various structures shown, the number and position of certain elements used as well as the character of the motive power employed without departing from the spirit of my invention.

I claim,

1. A flying machine comprising an aero-
plane having a substantially free periphery 105 capable of being impinged by the air and having an opening within its periphery of substantial depth in the fore and aft direction which is practically unobstructed, the depth of said opening in the fore and aft direction being equal to or greater than half the width thereof, and whereby an additional advancing edge is formed on the aero-
plane, the said first mentioned periphery and the periphery of the said opening being of different shape the former being curved and the latter angular, a car connected with 110 the said aeroplane, and a propeller mounted on the said car and constructed to move the same and the parts connected therewith horizontally.

2. A flying machine comprising an aero-
plane having a substantially free periphery 120 capable of being impinged by the air and having an opening within its periphery of substantial depth in the fore and aft direction which is practically unobstructed, the depth of said opening in the fore and aft direction being equal to or greater than half the width thereof, and whereby an additional advancing edge is formed on the aero-
plane the first mentioned periphery being 125

curved and the periphery of the said opening being of different shape the former being curved and the latter rectangular, a car connected with the said aeroplane, and a propeller mounted on the said car and constructed to move the same and the parts connected therewith horizontally.

3. A flying machine comprising an aeroplane having a substantially free periphery capable of being impinged by the air and having an opening within its periphery of substantial depth in the fore and aft direction which is practically unobstructed, the depth of said opening in the fore and aft direction being equal to or greater than half the width thereof, and whereby an additional advancing edge is formed on the aeroplane, said first mentioned periphery being substantially curved and the rear part of the periphery of the said opening being of different shapes the front part of the former being curved and the rear part of the latter being substantially straight, a car connected with the said aeroplane, and a propeller mounted on the said car and constructed to move the same and the parts connected therewith horizontally.

4. A flying machine comprising an aeroplane having a substantially free periphery capable of being impinged by the air and having an opening within its periphery of substantial depth in the fore and aft direction which is practically unobstructed, the depth of said opening in the fore and aft direction being equal to or greater than half the width thereof, and whereby an additional advancing edge is formed on the aeroplane the said first mentioned periphery and the periphery of the said opening being of different shape and eccentric one to the other the former being curved and the latter angular, a car connected with the said aeroplane, and a propeller mounted on the said car and constructed to move the same and the parts connected therewith horizontally.

5. A flying machine comprising an aeroplane having a substantially free periphery capable of being impinged by the air and having an opening within its periphery of substantial depth in the fore and aft direction which is practically unobstructed, the depth of said opening in the fore and aft direction being equal to or greater than half the width thereof, and whereby an additional advancing edge is formed on the aeroplane the said first mentioned periphery and the periphery of the said opening being of different shape and eccentric one to the other the former being curved and the latter quadrangular, a car connected with the said aeroplane, and a propeller mounted on the said car and constructed to move the same and the parts connected therewith horizontally.

6. A flying machine comprising an aeroplane having a substantially free periphery capable of being impinged by the air and having an opening within its periphery of substantial depth in the fore and aft direction which is practically unobstructed, the depth of said opening in the fore and aft direction being equal to or greater than half the width thereof, and whereby an additional advancing edge is formed on the aeroplane the said first mentioned periphery and the periphery of the said opening being of different shape and eccentric one to the other the front part of the former being curved and the rear part of the latter being substantially straight, a car connected with the said aeroplane, and a propeller mounted on the said car and constructed to move the same and the parts connected therewith horizontally.

7. A flying machine comprising an aeroplane having an outer periphery substantially in the form of a complete circle and an inner periphery of angular form the center of the circle and the center of the said angularly-formed inner periphery lying substantially along the median line, and a propeller mounted adjacent to the forward part of the said inner periphery and leaving a substantially unobstructed space in the rear of the said propeller for the impinging air to act against the following advancing edge.

8. A flying machine comprising an aeroplane having a substantially free periphery capable of being impinged by the air and having an opening within its periphery which is practically unobstructed and whereby an additional advancing edge is formed on the aeroplane the said first mentioned periphery and the periphery of the said opening being of different shape the former being substantially a complete circle and the latter angular, a car connected with the said aeroplane, and a propeller mounted on the said car and constructed to move the same and the parts connected therewith horizontally.

9. A flying machine comprising an aeroplane having a substantially free periphery capable of being impinged by the air and having an opening within its periphery which is practically unobstructed and whereby an additional advancing edge is formed on the aeroplane the said first mentioned periphery and the periphery of the said opening being of different shape and eccentric one to the other the former being substantially a complete circle and the latter angular, a car connected with the said aeroplane, and a propeller mounted on the said car and constructed to move the same and the parts connected therewith horizontally.

10. A flying machine comprising an aero-

4

plane having a substantially free periphery capable of being impinged by the air and having an opening within its periphery which is practically unobstructed and whereby an additional advancing edge is formed on the aeroplane the said first mentioned periphery and the periphery of the said opening being of different shape the former being substantially a complete circle and 5 the latter angular the rear part of the said circle being flexible, a car connected with the said aeroplane, and a propeller mounted on the said car and constructed to move the same and the parts connected therewith 10 horizontally.

11. A flying machine comprising an aeroplane having a substantially free periphery capable of being impinged by the air and having an opening within its periphery 20 which is practically unobstructed and whereby an additional advancing edge is formed on the aeroplane the said first mentioned periphery and the periphery of the said opening being of different shape the former 25 being substantially a complete circle and the latter angular, the rearward portion of said plane forming a pair of stabilizers mounted on the said aeroplane so as to turn the machine on its longitudinal axis, 30 a car connected with the said aeroplane, and a propeller mounted on the said car and constructed to move the same and the parts connected therewith horizontally.

12. A flying machine comprising an aeroplane having a substantially free periphery capable of being impinged by the air and having an opening within its periphery which is practically unobstructed and whereby an additional advancing edge is 35 formed on the aeroplane the said first mentioned periphery and the periphery of the said opening being of different shape the former being substantially a complete circle and the other angular the said aeroplane 40 being normally at a positive angle of incidence and curved in longitudinal cross section, a car connected with the said aeroplane, and a propeller mounted on the said car and constructed to move the same 45 and the parts connected therewith horizontally.

13. A flying machine comprising an aeroplane having an outer periphery substantially in the form of a complete circle and 55 an inner periphery of angular form the center of the circle and the center of the rectangle lying substantially along the median line of the aeroplane but at different points substantially in the said line, 60 a shaft, a propeller mounted on the said shaft adjacent to the forward part of the said inner periphery and leaving a substantially unobstructed space in the rear of the said propeller for the impinging air 65 to act against the following advancing edge.

14. A flying machine comprising an aeroplane having an outer periphery substantially in the form of a complete circle and an inner periphery of substantially rectangular form the center of the circle and 70 the center of the rectangle lying substantially along the median line of the aeroplane but at different points along the said line, an enclosed car or fuselage, a motor of the compression type on the said car, 75 a shaft mounted on the said motor in a line parallel to the said median line, propeller blades mounted on the said shaft adjacent to the forward part of the said inner periphery and leaving a substantially unobstructed space in the rear of the said propeller blades for the impinging air to act 80 against the following advancing edge the said advancing edge being part of a pivoted surface the rear part of the said pivoted 85 surface and the rear part of the said aeroplane being flexible.

15. A flying machine comprising an aeroplane normally inclined to the horizontal and curved substantially from front to rear 90 with its concaved side facing downwardly, a pair of controlling devices mounted one on each side of the longitudinal center line of the said aeroplane the rear of the said aeroplane being recessed to allow the said 95 controlling devices to be placed therein and said stabilizers being positioned with reference to the aeroplane such that the rear edges of the plane and the stabilizers normally form a substantially continuous unbroken line or rear edge, and means for 100 operating the said controlling devices.

16. A flying machine comprising an aeroplane normally inclined to the horizontal and curved substantially from front to rear 105 with its concaved side facing downwardly, a pair of controlling devices mounted one on each side of the longitudinal center line of the said aeroplane the rear of the said aeroplane being recessed to allow the said 110 controlling devices to be placed therein substantially the whole of the rear portion of the recess being occupied by said pair of controlling devices and the rearmost edges of both the said aeroplane and the said devices making substantially one continuous line, and means for operating the said controlling devices.

17. A flying machine comprising a body having a pointed covered forward portion, aeroplane surface extending rearwardly of the said body on either side of the longitudinal center line thereof with open space between the said extensions the front portion of the said aeroplane surface being normally higher than the rear portion thereof and the curve adjacent to the said front portion being of a different curvature than that adjacent to the said rear portion, auxiliary surfaces attached adjacent to the 115 120 125 130

said aeroplane surface, means for operating the said auxiliary surfaces, an operator's compartment in the said body, a motor mounted on the said body, a shaft substantially in alignment with the longitudinal center line of the said body mounted thereon, and a propeller mounted on the said shaft in the rear of the said body and adjacent to the forward portion of the said space between the said side extensions of the said aeroplane surface.

18. A flying machine comprising a body having a pointed covered forward portion, aeroplane surface extending rearwardly of the said body on either side of the longitudinal center line thereof with open space between the said extensions the front portion of the said aeroplane surface being normally higher than the rear portion thereof and the curve adjacent to the said front portion being of a different curvature to that adjacent to the said rear portion, auxiliary surfaces attached adjacent to the said aeroplane surface means for operating the said auxiliary surfaces, an operator's compartment in the said body, a motor mounted on the said body, a shaft substantially in alignment with the longitudinal center line of the said body as seen from a vertical view point mounted thereon, and a propeller mounted on the said shaft in the rear of the said body and adjacent to the forward portion of the said space between the said side extensions of the said aeroplane surface, the said body having the same general inclination as that of the nor-

mal positive inclination of the said aeroplane surface and the said propeller being at substantially right angles thereto.

19. A flying machine comprising an aeroplane surface having two substantially unobstructed advancing edges following one another normally inclined to the horizontal and curved substantially from front to rear with its concaved side facing downwardly, said surface comprising a pair of controlling devices mounted one on each side of the longitudinal center line of the said aeroplane the rear of the said aeroplane being recessed to allow the said controlling devices to be placed therein the rearmost edges of both the said aeroplane and the said devices making substantially one continuous line, and means for operating the said controlling devices.

20. A flying machine comprising an aeroplane normally inclined to the horizontal and curved substantially from front to rear with its concaved side facing downwardly, said aeroplane having a recess at its rear edge, controlling devices comprising a surface operatively positioned in the recess with its rear edge normally forming a continuous line with the rear edge of the aeroplane, and means for operating the control surface.

Witness my hand this twentieth day of December 1910.
